TRAILER HITCH

Jack E. Moll, New Berlin, Wis., assignor to Miller Tilt-
Top Trailer, Inc., Milwaukee, Wis., a corporation of Wisconsin

Filed July 29, 1965, Ser. No. 86,360

Term of patent 14 years

(Cl. D14—3)

FIG. 1

FIG. 3

FIG. 1 is a top view of a trailer hitch, portions being broken away for indeterminate length;

FIG. 2 is a side view of the trailer hitch.

FIG. 3 is a perspective view, the frame being shortened for convenience of illustration.

I claim:

The ornamental design for a trailer hitch, substantially as shown and described.
